UNITED STATES PATENT OFFICE.

HORATIO R. SWARTWOOD, OF TRACY, MINNESOTA.

SASH-HOLDER.

SPECIFICATION forming part of Letters Patent No. 633,924, dated September 26, 1899.

Application filed June 29, 1896. Serial No. 597,437. (No model.)

To all whom it may concern:

Be it known that I, HORATIO R. SWARTWOOD, a citizen of the United States, residing at Tracy, in the county of Lyon and State of Minnesota, have invented certain new and useful Improvements in Window-Sash Holders; and I do hereby declare the following to be a full, clear, and exact description of the invention, such as will enable others skilled in the art to which it appertains to make and use the same.

My invention relates to sash-fasteners.

My object is to provide an improved sash-fastener which will be adapted to hold the sash in raised position in a highly-superior manner and yet allow quicker and easier manipulation of the latter.

Having this object in view, the invention consists of a rack suitably fastened to the window-sash and improved spring-actuated mechanism adapted to coöperate therewith, as will appear more fully hereinafter.

In the accompanying drawings, Figure 1 is a sectional elevation looking toward the side 25 of the housing or casing which incloses the mechanism in the window-casing. Fig. 2 is a top sectional view taken on line $x-x$ of Fig. 1. Fig. 3 is a view looking toward the inner face of the housing or casing. Fig. 4 is a 30 front elevation showing the outer face of side casing or housing, and Fig. 5 is a vertical section taken through the casing and rack.

A designates the ordinary window-sash frame, and B the window-casing.

The numeral 1 designates a rack which is 35 preferably constructed of a ribbon of metal crimped into proper shape, and this rack is sunk in the face of the window-sash and is held in place by fastening devices 2.

The numeral 3 is a rectangular housing or casing having an inner face-plate 4. The body 3 of the casing is sunk in the window-casing, with the face-plate lying adjacent to the rack heretofore designated, screws 5 being employed to hold the casing in position. The face-plate and casing are provided with a vertical elongated slot 6, which is in communication with another cylindrical opening 7, that leads to the outer face of said casing. In 50 the upper portion of the vertical slot is a pinion 8, which is suitably journaled in the casing or housing 3 in such manner that its teeth

will project slightly beyond the face-plate and into engagement with rack 1.

I employ a flat release-spring 9. This release-spring has its lower end connected to the face-plate and the bottom of the slot 6 and its upper end free. The spring is so disposed and constructed that its upper end has a tendency to spring away from the pinion, 60 and hence when said spring is released the pinion is adapted to freely rotate, so that an up-and-down movement of the sash can be had. As will now appear, however, I employ improved means which is adapted to normally 65 keep this spring in engagement with the pinion, so that the latter is locked.

There is a plunger 10, which lies in opening 7 and has its inner end bifurcated, as shown at 11, the release-spring lying in this 70 bifurcation. One portion of the bifurcated end is formed into an inclined cam 11, which engages with the free end of the release-spring and holds the same in engagement with the pinion. The plunger is also provided with a 75 transversely-extending limit-pin 12.

I employ two screw-threaded bolts 13 and 14, which are secured for about half their length within casing 3 in such manner that the other half projects through the outer face 80 of said casing in the manner shown, adjusting-nuts 15 and 16 being provided. There is an adjusting-bar 17, which is free to slide on the outer ends of the bolts between the casing and the ends and through which the plunger 10 loosely passes. A coil-spring 18 encircles plunger 10 and is interposed between adjusting-bar 17 and limit-pin 12, whereby said plunger is normally forced inward and against release-spring 9, forcing the latter 90 into engagement with the pinion and holding said spring locked. By turning the nuts 15 and 16 one way or the other the adjusting-bar may be moved forward and the spring compressed, or it may be allowed to move outward, thereby decreasing the tension of said spring. 95

The operation is as follows: Let it be assumed that the window-sash is down and it is desired to raise the same and hold it at any 100 desired height. The plunger-rod is first pulled outward against the action of the coil-spring, thereby allowing the free end of the release-spring to spring out of engagement

with the pinion. The window may now be raised, as the pinion is now free to rotate and mesh with the rack on the window-sash as the latter is moved upward, the plunger being meanwhile held retracted by the operator. As soon as the desired height has been reached the plunger should be released, whereupon the coil-spring will force said plunger back, thereby causing the cam 11 to contact with the release-spring and push the free end of the latter into engagement with the pinion. It will be observed that the plunger locks the release-spring and pinion together, as it were, and thus prevents the window-sash from descending. When it is desired to lower the sash or raise it still higher, the operation may be repeated.

My invention is adapted for use in connection with any style of window sash and frame and may be readily applied thereto without material defacement; but it is peculiarly adapted for use in connection with railway-car windows which may be easily manipulated, thereby obviating the annoyance heretofore experienced in the use of such windows.

Having thus described my invention, what I claim as new, and desire to secure by Letters Patent, is—

1. In a sash-fastener, the combination with a window-sash and a rack located thereon, of a rotatable pinion, a flat releasing-spring having one end fixed and one end free, and a

spring-pressed plunger having a bifurcated end straddling the releasing-spring, said plunger being adapted to hold the free end of the releasing-spring normally in locked engagement with the pinion and said plunger being adapted for retraction to allow the releasing-spring to throw itself out of engagement with the pinion.

2. In a sash-fastener, the combination with a window-sash and a rack located thereon, of a rotatable pinion, a flat releasing-spring having one end fixed and the other end free, a plunger having a bifurcated end straddling the releasing-spring, an adjusting-bar loose on said plunger, a coil-spring encircling the plunger and interposed between the adjusting-bar and the bifurcated end thereof, and mechanism for adjusting the adjusting-bar, said elements being so disposed and related that the plunger normally keeps the free end of the releasing-spring in locked engagement with the pinion, and said plunger being adapted for retraction to allow the releasing-spring to throw itself out of engagement with the pinion.

In testimony whereof I have signed this specification in the presence of two subscribers.

HORATIO R. SWARTWOOD.
